UNITED STATES PATENT OFFICE.

EDWARD J. BRANDT, OF WATERTOWN, WISCONSIN, ASSIGNOR TO BRANDT AUTOMATIC CASHIER COMPANY, OF WATERTOWN, WISCONSIN.

CALCULATING MECHANISM.

Application filed April 19, 1919. Serial No. 291,208.

To all whom it may concern:

Be it known that I, EDWARD J. BRANDT, a citizen of the United States, residing at Watertown, in the county of Jefferson and

5 State of Wisconsin, have invented certain new and useful Improvements in Calculating Mechanisms, of which the following is a specification, reference being had therein to the accompanying drawing.

10 The invention relates to improvements in calculating or other similar mechanisms, capable of use in any field wherever such a mechanism is needed and more particularly to a machine of the type illustrated in my 15 pending application filed March 21, 1918. Serial No. 223,786.

Heretofore in the construction of calculating machines it has been customary to prevent the over-running, or over-throw of 20 the calculators after either an adding operation, or a resetting of the same by means of a positive stop or wedge, suddenly and abruptly arresting the movement of the calculators, thereby subjecting the entire 25 mechanism to a severe shock or strain.

It is an object of this invention to provide a mechanism in which the calculators are moved in a steady, smooth manner, and over-running or over-throwing after an adding process, or upon a resetting of the calculators is prevented without the shock or jar incident to these operations in the prior art structures. With this conception in mind the preferred embodiment of the invention 30 includes friction means for normally resisting the movement of the calculators to prevent an over-running when in the process of addition, and to also serve to rotate the calculators with their supporting shaft to reset 35 the same in a zero position, at which point they are engaged and held by suitable means overcoming the resistance of the friction connection between the wheels and the shaft. More specifically the invention embraces a 40 calculating mechanism including a shaft having loosely mounted thereon a series of calculating wheels, arranged in sets of two, the calculating wheels being in frictional contact at all times with friction elements rigidly secured to the shaft, so that during an adding 45 operation the calculators are moved against this friction resistance and the instant the adding operation is completed, the movement of the calculator ceases without a jar or 50 shock because of the friction existing be-

tween the calculators and their friction elements. Upon a resetting of the calculators the shaft is rotated moving with it the friction elements that turn or move the calculators in consonance with their movement, 60 bringing the calculators to a zero position where they are each stopped by a suitable means and retained in their proper normal position against the friction resistance offered by reason of the friction connection 65 between the shaft and the calculator wheels until all of the calculators are lined up at zero, at which time the stop means is lifted and the mechanism ready to operate.

The invention also has for one of its objects a mechanism by which the shaft carrying the calculating wheels is normally held in position against rotary movement by a 70 brake, but of course may be rotated manually against the resistance of the brake to enable the resetting of the wheels.

A further object of the invention is to provide resilient means for maintaining the calculator wheels at all times in contact with their friction elements.

Another object of the invention is to provide an improved mechanism for carrying from the primary calculator to the secondary calculator.

In the accompanying drawings I have 85 shown and described one embodiment of the invention, but it will be understood that many changes in the construction and arrangement of parts can be made without departing from the spirit of the invention. 90

In the drawings:

Figure 1 is a longitudinal sectional view through the machine.

Figure 2 is a view looking at one end of the machine with parts broken away.

Figures 3 and 4 are detail views of the adding wheels and carry over mechanism.

Figures 5 and 6 are detail views of the spider.

Figures 7 and 8 are views of the drum 100 brake.

Figures 9 and 10 are views of the stop bar.

Referring now more particularly to the drawings wherein like reference characters indicate corresponding parts, the numeral 1 105 represents a suitable base having secured thereto a cover portion 2 provided with the usual sight openings 3 through which the totals of the calculators or indicators are readily visible.

As a convenient form of operating means for the calculating mechanism to be later described, the casing is provided with a ledge 4 that is slotted as indicated at 5 for the reception of the keys 6 of any formation and number desired. The keys 6 have the usual finger caps 7 thereon bearing any reference character that may be needed, this of course depending upon the use for which the machine is to be employed, such for instance as a register, wage adder or cashier. The keys are normally maintained in the position disclosed in Figure 1 by the action of the coiled springs 8, one spring being employed for each key and coiled there-around with one edge seated upon the ledge and its other edge engaging a shoulder portion of the key urging the key upwardly to the position shown in Figure 1. A description of one key and its train of associated mechanism will suffice for all, it being understood that the mechanism is the same in each instance.

Below the ledge are positioned a plurality of plates 10, each plate being pivoted intermediate its end and to be engaged by one of the bevel portions 9 of the keys. The lower end of each plate 10 is connected to an operating rod 12 extending adjacent the bottom 1 and carrying a pawl 13 cooperating with the ratchet on the primary calculator or adding wheel of each set and of a structure to be hereinafter described. The rod 12 is normally held in an operative position by a spring 15 connected to the rod and to the casing, it of course being manifest that a rod is connected to each of the pivoted flaps 10. It will thus be seen that when any one of the keys 6 is actuated the same will be depressed against the tension of the spring 8 forcing the bevel portion 9 thereof downwardly, deflecting or rocking the appropriate plate 10 about its pivot. This rocking movement moves the rod 12 connected to the plate that has been actuated horizontally, bringing the pawl forward to contact with the primary adding wheel ratchet 12' moving the same a full step to correspondingly move the adding wheel one number forward. When the key is released the spring 8 returns the same to its normal position and the rod 12 is likewise pulled back to its normal position by the spring 15', the rearward movement of the rod 12 being limited by the engagement of a stop thereon with the walls of a suitable guide 14. In the foregoing I have described a convenient form of operating mechanism for the calculating devices which will now be described, but I wish it to be distinctly understood that my invention is not limited to this form of actuating means, but that any suitable actuating means may be employed as the use may require.

65 The adding mechanism controlled by the

actuating means hereinbefore described, preferably comprises a shaft 17 which passes through suitable aperture in the housing and is supported by the walls thereof. The shaft has rigidly connected therewith at 70 spaced intervals any appropriate number of disks 18 which are relatively thin and keyed to revolve with the shaft. These disks have arranged on each side thereof friction pads 19, preferably of a somewhat less diameter 75 than the disks and composed of any material desired, although preferably soft leather secured to the disks in any convenient manner. A pair of adding wheels 20 and 21 are arranged one on each side of each 80 disk 18, and as two of the calculating wheels comprise an operating set, and as each set is operated in the same manner, a detail description of one will suffice for all. The adding wheels or calculators are of a substantially light formation, having offset circumferential flange portions 22 and 23 of a slightly less diameter than the diameter of the wheels bearing numerals thereon in 85 equally spaced distances apart ranging 90 from 00 to 99 so that each set of wheels are capable of registering 9999 if necessary before the mechanism is reset. The wheels are loosely mounted on the shaft, and the periphery of each wheel is formed with 95 ratchet teeth 12', a hundred being disposed around each periphery and spaced an equal distance apart so that when the wheels are shifted one full ratchet they are moved forward one full digit. The ratchet of the primary wheel 20 is the only one engaged by the pawls 13 of the operating rods 12, the ratchet of the secondary wheel coming in 100 operation when it is desired to carry over from the primary wheel to the secondary, 105 as for instance when 99 is registered on the primary wheel then the next operation of the primary wheel will shift the secondary wheel one step forward bringing into view 110 the numeral 1 on the secondary wheel and 110 00 on the primary wheel. This carrying mechanism will be later specifically described.

As a convenient means for holding the adding wheels 20 and 21 at all times in frictional contact with the friction pads 19 there is mounted upon the shaft 17 by means of set screws 17' spiders 27, each spider having suitable arms 27', three being shown for the purpose of illustration, formed at their outer ends with enlarged portions 26' 120 adapted to receive and carry oppositely disposed plungers 25 and 26. The head portions 26' are formed with sockets 28' disposed out of alignment with each other and entirely separated receiving the springs 29 which urge or force the plungers 25 outwardly into contact with the sides of the calculator or adding wheels 20 and 21. These plungers 25 are disposed staggeredly so as 125 130

to take advantage of the entire width of the enlarged head of the arms 27' and permit the use of a spring of considerable strength to always hold the adding wheels firmly 5 against the friction pads 19. The spiders are, as before stated, fixedly secured to the shaft 17 and at all times exert a pressure upon the adding wheels due to the action of the plungers 25 under the influence of the 10 springs 29.

It will be understood that the adding wheels are operated upon the manipulation of the keys 6 and assuming that the proper key has been actuated to operate the set of 15 adding wheels disclosed, the rod 12 would be moved forward upon the depression of the key, the pawl 13 thereof engaging a ratchet tooth 12' on the primary adding wheel, moving this wheel against the frictional resistance offered by its contact with the pad 19 so that after it has been moved one or more 20 steps in its process of addition no over-running stop is needed, but on the other hand the instant the pawl 13 exerts no influence 25 upon its ratchet 12', then the movement of the primary wheel 20 has ceased, due to the frictional resistance offered by the friction pad 19 during the actual movement of this wheel through the medium of the pawl 13, 30 and no stop is necessary to prevent this over-running of the calculator wheel. The movement of the wheel when actuated by the pawl is a steady, smooth one and there is no sudden shock or jar incident to the ending of 35 each adding operation. The primary wheel 20 is moved step by step upon the proper actuation of its pawl 13 cooperating with the ratchet 12' until 99 steps have taken place, at which time the numeral 99 also appears through the sight opening 3 in the casing and to carry over from the primary 40 to the secondary adding wheel when a total of 99 has been reached, the primary wheel has arranged thereon adjacent that portion 45 of the wheel bearing the characters 99 a lug 30 positioned to engage a projection 31 extending into the space between the primary and secondary wheels 20 and 21 and connected to one side of the pawl 32 which is 50 normally thrown upwardly toward the axis of the secondary wheel by a spring 35. The pawl is pivoted outside of the ratchet wheel circumference and in addition to the spring 35 has a second spring 37 adapted to return 55 the pawl after a carrying operation. The pawl is seated upon a pivot pin 33 passing through an elongated slot 34 therein, which pivot slot allows a give to the ratchet 32 and permits the pawl to return to its seat 60 after an operation. Assuming now that the primary wheel has been moved until 99 is the total visible through the opening 3, the lug 30 carried thereby is then near the projection 31 of the carry over ratchet 32, and 65 another operation of the rod 12 will move

the primary wheel one step causing the lug 30 to engage the upstanding projection 31, shifting the pawl 32 upon its pivot to engage the ratchet 14' on the secondary wheel 21, and throw the same forward one full tooth or number overcoming the resistance of the pad 19, the pawl 32 being then returned to its normal position by the spring 37 urging the same rearwardly. After this action, the secondary wheel would 70 bear the reference character 1 indicating one full step forward, while the primary wheel would have been moved so as to indicate 00. The pawl 32 after each operation returns to its original position and is moved again 80 upon another complete revolution of the primary adding wheel, and this operation may be continued until the secondary wheel has been moved 99 full steps forward and the primary wheel moved 99 steps on its last 85 revolution and the mechanism will then register 9999.

During each movement of the primary or secondary wheels 20 and 21, they are, of course, actuated against the frictional resistance due to the contact of the sides of these wheels with the immovable friction pads 19, so that the instant any positive driving action upon either of the wheels is eliminated, then the movement of the wheels 90 instantly ceases by reason of its friction resistance offered as they are always held in frictional contact with the pads by the spring plungers 25 on the spiders keyed to the shaft. It will be understood that the primary ratchet wheels are given a step by step movement through the action of the pawl 13 on the operating rod 12, and of course should the ratchet be moved forward two 100 full teeth or steps, then the total in numbers 105 would be likewise moved two full numbers, for instance from 96 to 98.

After the mechanism has been used and it is desired to reset the calculator or adding wheels so that they all line up in the zero 110 position, the shaft 17 is rotated, being shifted through the medium of an operating handle 37' fashioned to fit within the keyway 35' of the shaft extending through one end thereof and a slight distance along one side. 115 This handle is provided with a locking detent 38 adapted to enter a socket 39 in the case when the shaft is not to be rotated. The shaft also carries a drum 38' positioned slightly within the interior of the case, fastened to the shaft by the set screws 39' and adapted to be engaged by the pivoted brake 40' by reason of the spring 41' secured to one end of the brake and to an appropriate portion of the case. This brake frictionally 120 assists in holding the shaft against a turning movement when the totalizers or calculators are in an adding operation, but when it is desired to rotate the shaft to reset the calculators the handle 37' is pulled out- 125 130

wardly to disengage the detent 38 from the socket 39 and the shaft is then rotated against the frictional resistance offered by the brake 40' until all of the calculator 5 wheels have been moved to the zero position by the disks 18 and friction pads 19 in contact with the calculators and are retained in this position by a stop which will now be described.

10 Each calculator wheel is provided with a suitable pin 45 extending parallel with the shaft from one side of each wheel, which pins are placed adjacent the 00 numerals on the drum portions of the calculator 15 wheels 20 and 21. When these wheels are to be reset an elongated stop 40 mounted upon the pivot 41 extending along the upper portion of the case is depressed by placing strain upon the hand knobs 43 against 20 the tension of the springs 42, so that the stops portions 44 of a width approximating the distance between the primary and secondary wheels of a given set are spaced apart and adapted to enter the space between these 25 wheels formed by reducing the diameter of the disks 18. When the stop is depressed it is held in this position while the shaft is rotated by the handle 37' moving the primary and secondary wheels 20 and 21 due 30 to the frictional connection between the shaft and the wheels through the medium of the friction pads 19, in the direction they move when in an adding operation, which movement continues until all of the 35 pins 45 cooperate with or engage the proper stop portions 44, which retain or hold the calculators wheels in their normal or zero position. Of course, as the shaft is rotated the pins of the various calculator wheels 40 usually engage the stops successively, and when one pin has engaged its stop the calculator wheel with which said pin is connected is brought to a standstill, but the shaft continues to rotate against the frictional 45 resistance offered by reason of the frictional connection between the disks 18 and the calculator wheels until all of the adding wheels are brought to their normal position, it being understood that first the pin 50 of one wheel, and then the pin of another engages the appropriate stop portion 44 until the entire set of wheels has been lined up at a zero position. After this resetting it is only necessary to remove any stress 55 from the handle portions 43, and spring 42 then immediately throws the elongated stop member upwardly bringing the stop portions 44 out from between the various sets of adding wheels and the mechanism is then 60 in condition for operation.

While I have disclosed the calculators or indicators 20 and 21 as being of a circular construction, it will of course be understood that any suitable type of indicator or calculator may be used without departing from

this invention. While I have herein disclosed the preferred embodiment of the invention, I wish it to be understood that said invention is capable of embodiments in other forms of devices differing in arrangement 70 and detail to the one herein illustrated, but which will be embraced within the spirit of the appended claims.

Having thus described the invention, what I claim is:

1. A machine of the character described comprising a shaft, an adding wheel rotatably mounted on the shaft, a friction disc secured to the shaft, spring controlled plungers adapted to exert their effective pressure 80 at separated points for forcing the adding wheel into contact with the friction disk, and means for overcoming the friction and rotating the adding wheel.

2. A machine of the character described comprising a shaft, an adding wheel rotatably mounted on the shaft, a friction disk secured to the shaft, a sleeve secured to the shaft, arms radiating from the sleeve and having enlarged outer ends provided with 90 openings therein, spring-pressed plungers carried in the openings and engaging the adding wheel for normally forcing the same into contact with the friction disk, and means for overcoming the friction and rotating the adding wheel.

3. A machine of the character described comprising a shaft, a series of pairs of adding wheels, rotatably mounted on the shaft, a friction disk secured to the shaft between the adding wheels of each pair, a sleeve secured to the shaft between each series of pairs of adding wheels, arms radiating from the sleeves and having enlarged outer ends provided with openings in the opposite faces 100 thereof, oppositely disposed spring-pressed plungers in the openings and engaging the adding wheels for normally forcing them into contact with the friction disk, and means for overcoming the friction and rotating the adding wheels.

4. A machine of the character described comprising a movable indicator, friction means adapted to normally remain still and resist the movement of the indicator when in a computing process, means for overcoming the resistance of said resisting means for operating the indicator, and other means for moving the frictional resisting means and likewise moving the indicator to reset the 110 same, said means including a shaft to which the frictional resisting means is rigidly attached.

5. A machine of the character described comprising a plurality of indicators, friction 115 elements immovable relative to said indicators during a computing operation thereof for resisting the movement of said indicators, means for maintaining said indicators in contact with the friction elements com- 120 125 130

prising oppositely disposed spring pressed plungers arranged in staggered relation and bearing against the indicators, and means for moving said indicators overcoming the resistance of the frictional resisting element.

6. A machine of the character described comprising a pair of indicators, friction elements disposed between said indicators to resist the movement thereof, means for 10 maintaining the indicators in contact with the friction elements comprising spring pressed plungers immovable relative to said indicators, and means for operating the indicators during a computing process overcoming the resistance of said friction elements.

7. A machine of the character described comprising a primary and secondary adding wheel, friction means interposed between 20 said wheels for resisting movement thereof, operating means cooperating with the primary wheel for moving the same in opposition to the frictional resistance of said friction means, and means for carrying over 25 from the primary to the secondary wheel after the primary wheel has made a revolution.

8. A machine of the character described comprising a primary and secondary adding 30 wheel, friction means interposed between said wheels for resisting movement thereof, operating means cooperating with the primary wheel for moving the same in oppo-

sition to the frictional resistance of said friction means, and means for carrying over 35 from the primary to the secondary wheel after the primary wheel has made a revolution, said last mentioned means comprising a ratchet cooperating with the secondary wheel and adapted to be engaged and shifted 40 by a projection on the primary wheel.

9. A machine of the character described comprising a pair of movable adding wheels, a shaft, a disk carried by said shaft, friction pads on said disk, means for maintaining 45 said adding wheels in contact with the friction pads to resist a movement thereof, and operating means for shifting the primary wheel overcoming the resistance of its friction pad.

10. A machine of the character described comprising a pair of movable adding wheels, a shaft, a disk carried by said shaft, friction pads on said disk, means for maintaining 55 said adding wheels in contact with the friction pads to resist a movement thereof, operating means for shifting the primary wheel overcoming the resistance of its friction pad, and means for carrying over from the primary wheel to the secondary wheel to move 60 the secondary wheel upon each revolution of the primary wheel.

In testimony whereof I hereunto affix my signature.

EDWARD J. BRANDT.
